UNITED STATES PATENT OFFICE.

GEORGE W. BOTHWELL, OF ONTARIO, CALIFORNIA.

FUEL-SUPPLY MEANS FOR ORCHARD-HEATERS.

1,145,289.

Specification of Letters Patent.

Patented July 6, 1915.

Application filed October 26, 1914. Serial No. 868,573.

To all whom it may concern:

Be it known that I, GEORGE W. BOTHWELL, a citizen of the United States, residing at Ontario, in the county of San Bernardino and State of California, have invented a new and useful Fuel-Supply Means for Orchard-Heaters, of which the following is a specification.

This invention relates to means for supplying fuel such as petroleum, to heaters or stoves used in heating orchards to protect the same from frost, and it relates particularly to fuel supply means in which the fuel is supplied gradually from a tank, in such manner that a uniform flow of fuel is obtained, irrespective of the amount of fuel in the tank, such uniformity in the flow being obtained by holding the fuel in the tank by the action of a partial vacuum produced above the fuel, the fuel being allowed to flow from the tank to an outlet chamber in communication with the outer air, whenever the fuel in said outlet chamber falls below a certain level and allows air to pass into the tank, the fuel then passing from said outlet chamber through a regulating valve, to the burner. An important object of the invention is to provide for quickly and conveniently draining the tank sufficiently to establish the condition of partial vacuum therein, and for then arresting such draining action so as to leave the feed under control of the regulating valve.

Another object of the invention is to prevent dirt, etc., from passing to the regulating valve and clogging the same.

A further object of the invention is to provide the fuel supply means with means for conducting the fuel to a heater or burner, such conducting means being flexibly or movably connected with the tank so as to facilitate adjustment of the conducting means to different positions, and to prevent undue strains on the parts by careless handling thereof, such as would be liable to occur if the pipe were rigidly connected to the tank.

Another object of the invention is to provide for folding the pipe or pipes connected to the tank to upright position close to the tank, so as to occupy a minimum of space, and safeguard against leakage when the device is not in operation, and also against damage to the pipe connections.

Another object of the invention is to

provide for draining off any water which may be in the oil used as fuel.

The accompanying drawings illustrate my invention, and referring thereto:

Figure 1 is a side elevation of the tank, 60 and the means for controlling the fuel supply therefrom. Fig. 2 is a side elevation of the said parts, in folded position. Fig. 3 is a section on line x_3-x_3 in Fig. 1, Fig. 4 is a section on line x_4-x_4 in Fig. 3, Fig. 65 5 is a partly broken plan view of the parts shown in Fig. 3. Fig. 6 is a partly broken elevation of a modification.

1, designates a fuel tank, provided with an opening through which it may be filled, 70 said opening being normally closed by a plug 2, which is adapted to make a tight closure, so as to retain a partial vacuum in the tank, as hereinafter set forth. For this purpose a screw plug may be used, the top 75 of the tank having an annular recess 2', surrounding this plug to receive grease or heavy oil for making an air tight closure. Said tank is provided near its lower end, with outlet means 3 consisting of a pipe 80 connected to the tank and having a valve 5 therein to shut off or turn on the oil supply to the heater. The outer end of this outlet means 3 is connected to a fitting 6, formed as a side opening L or a three way fitting 85 having an inlet opening 7 connected to said outlet means for the tank, a bottom opening 8 connected to a regulating valve 10 and a side opening 9 connected to a nipple 11 to which is connected an air inlet pipe 12. 90 Regulating valve 10 is preferably a needle valve, having its inlet connected to the opening 8 of the fitting or connection means 6, by means of a bushing 20 in said opening, and having its outlet connected to a delivery 95 pipe 13 leading to the burner or heater 14. The connection between regulating valve 10 and the delivery pipe 13 is preferably by means of an elbow 15, having its arm connected to the valve and pipe respectively, by 100 screw joints which are sufficiently loose to permit the pipe to turn on the elbow, in a horizontal plane, and the elbow to turn on the valve, in a vertical plane, these connections forming a universal joint, so that the delivery pipe may be swung horizontally or vertically without changing the position of the tank or straining the connections. Delivery pipe 13 is preferably formed with a bend or elbow indicated at 18' to enable it 110

to extend horizontally. By this means I provide for shifting the delivery pipe to accommodate it to various positions of the heater, without having to shift the tank, and I also obviate any liability of straining the pipe connections to the tank by careless handling thereof. This construction also permits the delivery pipe to be folded up against the tank, as shown in Fig. 2, so as 10 to make the device more compact for handling and storage.

The air inlet pipe 12 is also preferably swingingly mounted on the nipple 11, so that it can be turned either to raised position, as shown in full lines in Fig. 1, with its upper end resting against the tank, and extending above the outlet means and substantially to the level of the top of the tank, so as to be above the maximum height 20 of the fuel in the tank, or to lowered position, as shown in dotted lines in Fig. 1, with the outer end as low as the outlet means.

In order to prevent the needle valve 10 from being clogged by dirt which may be in the fuel, I prefer to provide a strainer 16, formed, for example, of wire gauze, rolled in the form of a thimble, with one end closed as shown at 16', such thimble being 25 slipped into the interior chamber 17 of the fitting 8, so as to extend vertically, with its closed end uppermost, and with its lower end resting on top of the bushing 20, and its cylindrical portion extending opposite the 30 oil inlet opening 7 and air inlet opening 9 of the fitting. When so placed the strainer extends in the path of the fuel passing from the outlet means 3 of the tank to the regulating valve, but a space 19 is left between 35 said strainer and the wall of the fitting, to permit air to pass alongside the strainer, from air inlet opening 9 to the outlet means 40 3 for the tank.

The heaters with their fuel supply tanks 45 are suitably distributed in the orchard to be protected, and said tanks are preferably charged with fuel some time before protection is needed. To charge the tank, the plug 2 therefor is removed, and shut off valve 5 is closed, and fuel, such as distillate 50 or other hydrocarbon oil is poured into the tank until it is about full. In case there is any water in the oil in the tank, I prefer to let the tank stand after filling for a sufficient 55 time to allow the water to settle out, and then, by turning down the pipe 12 to position shown in dotted lines in Fig. 1, and opening valve 5, this water is drained off, the plug 2 being open at this time to allow 60 the water to flow out freely. When all the water is drained off, valve 5 is closed, plug 2 is replaced and tightly closed, and valve 5 is again opened. Oil will then flow from 65 the tank, through outlet means 3 and pipe 12, until a partial vacuum is produced in

the upper part of the tank, above the oil therein, sufficient to overcome the hydrostatic head of the oil remaining in the tank. The shut off valve 5 is then closed, and the pipe 12 is swung up to position in which it 70 rests against the tank, which then supports it in upright position, and the device is then ready for operation at any time. The regulating valve 10 is set to allow the oil to feed through the delivery pipe 13 at the 75 proper rate for operation of the burner, under the head due to the body of oil in the outlet and fitting, this valve being always left in such set condition, and the turning on and off of the fuel being effected by the 80 shut off valve 5.

The operation of the device is as follows: When the heater is to be started, the shut off valve 5 is opened, and oil then flows through the outlet means 3 to the fitting 6, until said 85 parts are filled to the level of the top of the outlet means, the feed from the tank then ceasing until the level falls again sufficiently to allow some air to enter the tank through the air inlet pipe 12 and the outlet means 3. The oil so entering the fitting 6 also fills the 90 space above the regulating valve, in the fitting, and the connection thereto, and this space constitutes a well, holding enough oil to maintain a fairly constant flow through 95 the regulating valve to the heater 14. The oil being lighted at the heater, burns steadily and uniformly throughout the operation thereof. The partial vacuum in the tank holds the oil back until the oil in the fitting 100 6 lowers below the top of the inside of the outlet pipe 3, when a bubble of air will enter the air pipe 12, pass through the shut off valve 5 and enter the tank, then oil will flow until the seat of the valve 5 is flooded, cutting off the air, thus maintaining a constant 105 even pressure on the regulating valve regardless of the depth of oil in the tank. This operation makes a uniform fire from the time the shut-off valve is opened until 110 the last of the oil is consumed, or the shut off valve is closed again.

When the device is not in use I prefer to close the shut off valve 5, so as to hold the oil in the tank and to prevent expulsion of 115 oil by pressure of the vapor generated in the tank during hot weather. The air pipe 12 is preferably of sufficient height to extend, when raised, to or above the level of the top of the oil in the tank, so that if the 120 shut off valve leaks or is not tightly closed, any oil passing to the fitting simply rises in said pipe, and does not waste on the ground. The oil delivery pipe 13, being also raised to upright position, as shown in Fig. 2, when 125 the device is not in use, prevents leakage of oil through said pipe.

Instead of the regulating valve, other regulating means may be used. In general, the setting of this regulating valve is more 130

- or less permanent, or seldom requires to be changed, so that in some cases, a fixed regulating device, such as a reducing plug formed with a contracted opening, may be used, as shown at 10' in Fig. 6. This figure also shows the fuel supply means constructed without the strainer, and having a rigidly connected upright air inlet pipe 12^a, connected to the oil outlet means 3 by a 10 T fitting 6', so as to communicate therewith between the fuel tank and the regulating means 10'.
- What I claim is:
1. In a fuel supply means for orchard heaters, a fuel tank, an outlet means communicating with the lower portion of said tank and provided with a delivery pipe for supply of fuel from said tank, and an air inlet pipe communicating with said tank 20 and mounted to swing thereon, so as to extend upwardly in normal operation, for admission of air to the tank, and to swing down to position for draining fuel from the tank through said air inlet pipe.
  2. In a fuel supply means for orchard heaters, a fuel tank, an outlet means communicating with the lower portion of said tank and provided with a delivery pipe for supply of fuel from the tank, and an air 30 inlet pipe connected to said outlet means and mounted to swing vertically to bring it to raised position for normal operation thereof as an air inlet means, or to bring it to lowered position for draining fuel from said tank, and a valve in said outlet means between the tank and said air inlet pipe.
  3. In a fuel supply means for orchard heaters, a fuel tank, an outlet means therefor, a delivery pipe connected to said outlet 40 means and provided with a regulating valve, and an air inlet and fuel draining pipe connected to said outlet means between the fuel tank and said regulating valve and mounted to turn, to lower the outer end of said pipe below, or raise it above, said outlet means.
  4. In a fuel supply means for orchard heaters, a fuel tank, an outlet means therefor, a delivery pipe connected to said outlet means and provided with a regulating
- valve, an air inlet and fuel draining pipe 50 connected to said outlet means between the fuel tank and said regulating valve, and swingingly mounted to raise its outer end above, or lower it below, the outlet means, and a shut off valve in said outlet means 55 between said tank and the connection of said air inlet and fuel drain pipe.
5. A fuel supply means for orchard heaters comprising a fuel tank, an outlet means therefor, a fitting having a fuel inlet opening communicating with said outlet means, and having an air inlet opening and a fuel outlet opening, a strainer within said fitting and retained in place by engagement with the walls of said fitting, said strainer extending 60 in the path of the fuel from said fuel inlet to said fuel outlet opening, and being spaced from the wall of the fitting adjacent the air inlet opening to provide a passage for air from said opening to the outlet means for 65 the tank, without passing through the strainer.
6. A fuel supply means for orchard heaters comprising a tank, having an outlet means, a fuel delivery pipe connected to said 70 outlet means, and mounted to fold against the tank, and an air inlet pipe connected to said outlet means and mounted to fold against the tank.
7. A fuel supply means for orchard heaters, comprising a fuel tank having an oil outlet means at its lower portion, a regulating means connected to said oil outlet, an upright air inlet pipe connected to said oil 75 outlet means to admit air thereto between the fuel tank and the point of connection of said air inlet pipe.
- In testimony whereof I have hereunto set my hand, at Los Angeles, California, this 16th day of October, 1914.
